UNITED STATES PATENT OFFICE.

THOMAS B. ATTERBURY AND WM. WARWICK, OF PITTSBURGH, PENNSYLVANIA, ASSIGNEES
TO WARWICK, ATTERBURY & CO., OF PITTSBURGH, PENNSYLVANIA.

FACE-PLATE FOR LOCKS.

Specification of Letters Patent No. 15,456, dated July 29, 1856.

To all whom it may concern:

Be it known that we, THOMAS B. ATTERBURY and WILLIAM WARWICK, both of Pittsburgh, in the county of Allegheny and State 5 of Pennsylvania, have invented a new and useful Improvement in Right and Left Hand Locks; and we do hereby declare that the following is a full and exact description thereof, reference being had to the accompanying drawings and to the letters of reference marked thereon.

The nature of our invention consists in using for a lock or other fastening, a distinct and separate guard or face plate, which 15 is shaped in such a manner in relation to the case or skeleton frame of a lock, that it can be placed on either of the two sides of said case or skeleton frame, whereby the said lock or fastening may be used on doors, 20 which open to the right or to the left-hand side, the face plate being always put on the outside.

To enable others, skilled in the art to make and use our invention, we will proceed 25 to describe its construction and operations.

In the accompanying drawings Figure 1 is a perspective view of the case or outside of a lock; Fig. 2, a perspective view of the separate guard or face plate; Fig. 3 a section through the line I—II of the lock case (Fig. 1) and of the face plate (Fig. 2), the face plate being placed on the one side of the case.

A, A, is the case of a lock, which case may 35 be of any known shape, close or perforated by openings, as for instance, shown at a, a; b, b, are the screw holes, by which the lock is fastened to the door; c, c, the key-hole; d, d, the knob shank opening.

B, B, is the separate guard or face plate, which is provided with openings, corresponding to the openings b, b, c and d, of the lock case, viz: b' b', openings for the fastening screws; c', opening for the key, 40 and d' for the knob shank. The face plate is fastened down on the lock case, by means of the same screws, by which the lock is fastened to the door. As the screw holes, 45 key and knob shank openings (b, b, c and

d) are in the same position on the other 50 side of the lock, and also the corresponding holes b' b' c' and d' on the other side of the face plate. The same face plate will naturally fit on the other side of the lock, so that by said plate either of the sides of the 55 lock can be made the face.

The advantages in the use of a separate face plate are: that it can be finished by itself; thus in japanning or enameling it, it may be "dipped" into the japanning or 60 enameling substance; when in ordinary locks, where the face or faces are to be finished, when connected with the lock parts, the japanning or enameling substance has to be "brushed" or painted on with great 65 care, notwithstanding which the substance is apt to enter into the openings of the case, preventing thereby the parts of the lock to operate, and making it necessary to be cleaned out again; the lock case, when it 70 has the separate face plate does not require any finish, as far as the plate covers it, and it can be made in any shape, best suitable for the purpose of keeping the parts of the lock together, without any regard to its 75 external appearance, or it may be a mere skeleton frame. As the face plate forms a part, which has no immediate connection with the operating parts of the lock or fastening, it may get injured or broken without injury 80 to the lock itself.

Having thus fully described our improvement, what we claim herein as new and desire to secure by Letters Patent is—

The separate or distinct guard or face 85 plate of such a form in relation to case or skeleton frame of a lock or other fastening, that it may be put on either of the two sides of the said case or frame, whereby either of the sides can be made the face of 90 the said lock or fastening, substantially as described.

THOS. B. ATTERBURY.
WILLIAM WARWICK.
